UNITED STATES PATENT OFFICE.

WILLIAM BOTTOMLEY KEIGHLEY, OF VINELAND, NEW JERSEY.

COMBINED BAND-KNIFE INSEAM-TRIMMING MACHINE AND WELT-POUNDING DEVICE.

1,032,219.

Specification of Letters Patent.

Patented July 9, 1912.

Application filed February 1, 1911. Serial No. 605,918.

To all whom it may concern:

Be it known that I, WILLIAM B. KEIGHLEY, a citizen of the United States, and a resident of Vineland, Cumberland county, New Jersey, have invented certain Improvements in Combined Band-Knife Inseam-Trimming Machines and Welt-Pounding Devices, of which the following is a specification.

10 One object of my invention is to provide a novel and relatively simple machine for simultaneously trimming the inseams of shoes and pounding or beating the welts thereof; it being particularly desired that the machine shall be simple and substantial in construction as well as efficient in action, and have its parts so arranged as to render possible a high speed of operation.

Another object of the invention is to provide novel mechanism for feeding a shoe to be trimmed to a band knife or other form of cutter; it being further desired that the machine shall include novel means for causing a hammer to pound or flatten the welt of a shoe while it is being trimmed by this particular form of cutter.

I also desire to provide a welt beating attachment for an inseam trimmer with improved means whereby it is possible to pound or flatten the welt at the same time it is being trimmed by the knife or cutter, without interfering with the action of the latter; the invention also contemplating a novel device for adjusting the parts of the apparatus to permit of the introduction or entrance of the work.

I further desire to provide a device of the character described with novel means for supporting a shoe while it is being simultaneously acted on by an inseam trimmer and a welt beater; the invention also contemplating improved means for taking up the force of the blows of the hammer.

These objects and other advantages 45 ends I secure as hereinafter set forth, reference being had to the accompanying drawings, in which;—

Figure 1, is a front elevation of a machine constructed according to my invention; Fig. 50 2, is a side elevation of the machine shown in Fig. 1; Fig. 3, is a plan partly in section on the line *a—a*, Fig. 1; Fig. 4, is an enlarged horizontal section on the line *b—b*, Fig. 1; Fig. 5, is a front elevation on an enlarged

scale showing the detail arrangement of certain of the parts of the machine, and Fig. 6, is an end elevation of the hammer.

In the above drawings, 1 represents a portion of the main supporting frame of the machine constituting my invention which has a vertical post 2, and a pair of standards 3 and 4 which carry a transverse member 5 having mounted on it a work supporting post 6 supported in a slideway so as to be movable toward and from the front of the machine. There is also a band knife or cutter 7 whose operative vertical run is shown in Figs. 1 and 2 and whose second vertical run is shown in Fig. 3 at 7^a. The work supporting post 6 has its top downwardly inclined away from the knife 7, being recessed for the reception of a reciprocable bar 9 held in place by a cover plate 9^a and abutting on an adjustable vibratory device 19 hereafter described. The post 6 has a vertical and preferably undercut slot in its front face and in this slides a block 8 yielding supported on a spring 8^a which is positioned by a pin 8^b carried by a structure 50 projecting from said post 6. On the upper end of the block 8 is mounted a work supporting saddle 10 formed with a vertical plane face immediately adjacent the knife 7 and provided with an anti-friction disk 11 mounted in or on said face to facilitate the passage of work over it. The top surface of the saddle is inclined backwardly and its rear portion is slotted or recessed for the reception of the upper end of a lever 9^b pivoted at 9^c to the upper end of the post 6. The lower end of said lever abuts on the upper end of the reciprocable bar 9 which is likewise slotted for its reception and the spring 8^a normally maintains the saddle in contact with the lever, thereby holding said lever in engagement with the bar 9. With this construction it is possible for the saddle to move downwardly in order to permit of the passage of an abnormally large body of material, although at all times it remains in operative engagement with the bar 9 through the lever 9^b and receives vibratory movement therefrom.

Connected to the rear portion of the member 5 by a pin 17^c is a flat casing 12 so mounted as to be free to vibrate or move to a limited extent in a plane toward or from the band knife, 7, although its motion is re-

sisted and to some extent limited by a spring 13 which extends, in the case illustrated, between its lower portion and a set screw 14 adjustably mounted in the rear end of said member 5. It is obvious that by moving this screw up or down and retaining it in any adjusted position by means of a set screw 15, the effect of the spring 13 upon the possible swinging of the casing 12 may be varied 10 within certain limits. Said casing has bearings for a shaft 16, which has fixed to it within the casing a segmental or other eccentrically mounted weight 17, while outside of the casing it carries a driving pulley 18. Said weight 17 is provided with a number 15 of threaded holes as shown into which may be screwed any desired number of screws or plugs in order to increase or vary its weight within certain limits. The bar 9 is adjustably engaged by an adjustable screw or bolt 19 threaded into a projection 17^a of the casing structure 17.

Projecting horizontally from the casing structure toward the band knife 7 is a hammer 20 whose head is immediately adjacent said knife and whose opposite end is adjustably connected to said casing structure by a set screw 21. For the purpose of regulating the position of this hammer 20 with the utmost degree of nicety, I provide the casing with a socket 22 for the reception of the end of the hammer and mount in it a pair of co-acting wedges 23 and 24 whereby said hammer may be moved to any desired extent toward or from the knife 7. For the purpose of this adjustment there is formed on the structure 12 a lug 25 through which passes the adjusting screw of the wedge 23 whose larger end extends downward. The second wedge 24 has a projection from its smaller or lower end also passing through the lug 25 and threaded for the reception of adjusting and holding nuts as shown. Both of these wedges are 40 mounted in an opening of the socket 22 so that the wedge 24 is capable of engaging the rear end of the hammer in order to force it toward the knife 7 when either of said wedges has been suitably moved. After 45 adjustment the hammer is retained in any given position by means of the set screw 21. As shown in Figs. 4 and 6, the hammer head is provided with a relatively deep recess for the free passage of the operative 50 run 7 of the band knife, and its main portion or portions extend across the plane of said knife to engage or lie adjacent an abutment hereafter described.

Extending horizontally from the post 2 55 of the frame are any desired number of arms 27, 27^a and 28, of which the latter carries a pair of guards 29 and 30 for the in-operative vertical run of the knife 7, while the second serves to support a clapper 31

which extends vertically on that side of said 6: knife opposite the hammer. The lower end of the clapper is immediately adjacent and normally in contact with the operative face of said hammer. In addition the arm 27^a carries a pair of knife guards 32 and 33. 70

It is obvious that any blow struck by the hammer tends to cause an outward movement of the clapper 31, since this latter is supported on a hinge or pivot pin 34 and is in addition normally acted on by a spring 75 35 so that its lower end tends to move away from the hammer head. It is, however, held in place with its lower end against or immediately adjacent the hammer head by means of a wedge 38 and a block 36 carried 80 on the outer end of the arm 27 and tied by a tension member 37 to the rearwardly projecting end of the arm 28. This block or abutment is provided with an opening for the reception of the lower end of the clapper 85 31 and also for the adjustable wedge 38 which is designed to slide between the outer face of the said clapper and the block under the action of a lever 39 fulcrumed or pivoted on the upper end of a bar 40. The 90 opposite end of this lever is connected through a rod 41 with a foot treadle 42 and is normally held in the position shown by a spring 45 which in the present instance is attached to said treadle. 95

A set screw 43, mounted in a suitably formed lug 44 of the wedge 38 so as to engage the block 36, serves to limit the distance which said wedge may be lowered under the action of the lever 39, for said 100 block forms an abutment between which and the clapper 31 the wedge 38 may be inserted in order to normally prevent deflection or swinging outward of the lower end of said clapper under the action of the hammer 20 105 and of the spring 35. It is evident that with the withdrawal of the wedge 38, the hammer 20 will, under the action of the spring 110 13 tend to move against and possibly strike the band knife, even though the knife recess in said hammer be relatively deep, and in order to prevent this, I provide an adjustable abutment on the tension member 37 placed to co-act with a suitable structure carried by the casing 12. For this purpose 115 I fasten to the tension member a block or projecting lug 55 in which is a passage threaded for the reception of a headed screw or bolt 56 extending toward the casing 12 which is provided with a recess for 120 the reception of a rawhide or rubber plug or block 57. These various parts are so arranged that the head of the screw 56 is in such a position as to be engaged by the plug 57 whenever the casing 12 moves nearer 125 than a predetermined amount toward the band knife. It is understood that suitable set screws or other equivalent means are

provided for maintaining the screw 56 and the block or rod 57 in any given positions.

Under operating conditions the band knife is driven at a high speed with its vertical run 7 moving upwardly, while in addition the pulley wheel 18 and with it the shaft 16 are also turned at a high rate of speed. This causes revolution of the segmental or eccentrically mounted weight 17 on said shaft, so that this and the casing structure 12, are given a limited vibratory movement depending to a slight extent on the adjustment of the spring 13 but mainly upon the mass of the weight 17 and the speed of the shaft 16. The rod 9, which is operatively connected to the casing structure as heretofore described, is thus caused to rapidly reciprocate and through the lever 9^b impart a vibratory or vertical reciprocating movement to the work supporting saddle 10 which engages its upper end. Such a movement of said saddle facilitates or renders possible the free passage over it of the shoe to be trimmed, which is supported in the position shown in Fig. 5, and at the same time the saddle is free to move downwardly away from the hammer and clapper for an abnormal distance to permit of the passage of unusually thick bodies of material. The disk 11 also helps to render easy the passage of the work over the saddle, as it materially reduces the friction.

When it is desired to operate on a shoe, a downward movement of the treadle 42 turns the lever 39 on its pivot and raises the wedge 38, thereby permitting the lower end of the clapper 31 to move away from the knife and hammer under the action of the spring 35, after which the shoe is placed in the position shown with the welt between the clapper on one side, and the knife 7 and hammer on the other side, being supported largely on the saddle and to some extent by the duck bill plate 58. With this disposition of parts, the stock which it is desired to trim off projects across the plane of the knife and the release of the treadle permits the rising of the link or rod 41 under the action of the spring 45, so that the wedge 38 is again inserted between the block or abutment 36 and the clapper 31, forcing this latter into engagement with the welt of the shoe operated on and clamping the latter between itself and the head of the hammer.

It will be seen from Fig. 1 that the clapper is wedge shaped; its lower end, which projects below the lower face of the block 36, being relatively thin and rounded in order that it may enter and follow the crease of the shoe. When, therefore, the shoe is moved rearwardly, this end, moving through the crease, serves both as a guide to direct and a stop to limit such movement. When the shaft 16 is driven as above noted, the

vibratory movement of the casing structure 12 is imparted to the hammer 20 so that this is caused to reciprocate in a horizontal line and to coöperate with the abutment 36 to flatten or beat the welt of the shoe as the latter is fed rearwardly.

Since the surplus welt and stock project across the vertical plane of the knife or cutter 7, they are severed or trimmed away as the shoe is fed toward the rear of the machine, and the continuous vibration or trembling of the saddle 10 materially aids such rearward movement, since if a work supporting structure be employed which is motionless, the work has a tendency to stick or bind thereon. At the same time that the surplus material is trimmed from the shoe, the main portion of the welt is caused to pass between the face of the clapper 31 and the hammer 20 as above described and since this latter is rapidly vibrated or reciprocated by the unbalanced structure formed by the shaft 16, the weight 17 and the casing 12, said welt is flattened and slightly extended; the clapper being unyieldingly supported so as to form a solid abutment, by means of the wedge 38 and the block 36. As above noted this block is unyieldingly held by the arm 27 and the tension member 37. The strength of the blow struck by the hammer, as well as the amount of reciprocation imparted thereto, may be regulated by adjusting the spring 13 or by inserting or removing some of the screw plugs of the weight 17.

The position of the hammer head relatively to the knife 7 and the clapper 31 may be adjusted by raising or lowering the wedge 23 after the set screw 21 has been loosened; the hammer thus being forced toward the knife or being capable of movement away from the same as may be desired, after which it may be retained in position in the holder 22 by means of the set screw 21. As before noted the hammer is held from too close an approach to the knife by reason of the engagement of the screw 56 with the rod or plug 57.

The position of the clapper 31 when the wedge 38 has been inserted, is determined by the adjustment of the screw 43 carried by said wedge, since this is so placed that it strikes the top surface of the block 36 when the wedge has been forced down by the lever 39 to the extent necessary to bring and hold the clapper 31 in the desired position. The position of the saddle 10 relatively to the hammer 20 may be varied by the adjustment of the screw bolt 19 in the projection 17^a as the longitudinal movement of the bar 9 turns the lever 9^b on its pivot, and thereby either forces the saddle down or permits it to rise under the action of the spring 8^a.

While the vibratory movement of the cas-

ing 12 under operating conditions may be regulated as above noted, it is obvious that if desired, the portion 17^b of the casing structure, instead of being loosely attached 5 to the member 5 by the pivot 17^c as shown, may be rigidly connected thereto. In such case this portion may be made in the form of a laterally flexible spring without departing from my invention.

10 I claim:—

1. The combination of a band knife; means for supporting a shoe adjacent said knife; and a hammer for beating the welt of a shoe while it is being trimmed; said knife 15 having a straight run extending on opposite sides of the hammer in a plane substantially parallel with and immediately adjacent to the operating face of said hammer.
2. The combination of a band knife; 20 means for supporting a shoe adjacent said knife; and a hammer placed to beat the welt of a shoe both in front of and behind the knife, while the latter is trimming the inseam of said shoe.
3. The combination of a band knife; 25 means for supporting a shoe adjacent the vertical run of said knife; an abutment on one side of said run; and a hammer on the opposite side thereof; with means for actuating said hammer.
4. The combination of a band knife; 30 means for supporting a shoe in a position adjacent said knife; a hammer independent of said supporting means for beating the welt of the shoe while it is being trimmed by said knife; and means for simultaneously vibrating said shoe supporting means and said hammer.
5. The combination of a band knife; 35 means for supporting a shoe adjacent said knife; an abutment on one side of the knife; a hammer placed on the opposite side of the knife in position to co-act with said abutment; with a device common to the hammer 40 and to the shoe supporting means for simultaneously vibrating them.
6. The combination of a band knife; 45 an abutment mounted adjacent thereto; a hammer placed to co-act with said abutment; and means including a vibratory unbalanced rotary member for reciprocating said hammer.
7. The combination with a band knife of 50 a hammer mounted adjacent thereto; an abutment; and means for actuating said hammer consisting of a movable structure operative on the same; a vibratory unbalanced rotary member connected to said structure for reciprocating the same; and 55 means for actuating said rotary member.
8. The combination with a band knife of 60 a welt beating member adjacent thereto; and means for actuating said member consisting of a vibratory casing; a shaft there-

in; an eccentrically placed weight mounted 65 on said shaft; and means for turning the shaft with the weight to vibrate the casing and reciprocate the welt beating member connected thereto.

9. A welt beating device consisting of a 70 hammer; an abutment placed to co-act with same; a vibratory, unbalanced, rotary member operative on the hammer to reciprocate the same; and means for actuating said rotary member.

75

10. A welt beating device consisting of a 75 hammer; an abutment placed to co-act therewith; a shaft; a weight mounted on the shaft; a structure supporting said shaft and connected to the hammer; said structure being 80 free to vibrate under the action of said weight when the shaft is turned; with means for turning the shaft.

11. The combination in a welt beating device of a supporting structure; an abutment thereon; a reciprocable hammer; a structure connected thereto and movably mounted on the supporting structure so as to be free to vibrate; a shaft mounted in 85 said movable structure; means for driving 90 the shaft; and a weight mounted on the shaft with its mass unsymmetrical to the axis thereof.

12. The combination in a welt beating device of an abutment; a hammer; means 95 for actuating said hammer; a clapper structure movably interposed between the hammer and the abutment for directly supporting a welt while it is being acted on by the hammer; and a work support independent 100 of the clapper and abutment.

13. The combination of a supporting structure having an abutment; a hammer; means for actuating said hammer; a band knife having a portion adjacent the hammer; a clapper structure movably mounted 105 between the abutment and said hammer for supporting a welt while it is being acted on by the hammer; and a work support immediately adjacent the band knife mounted 110 to one side and independent of the abutment and clapper.

14. The combination in a welt beating device of a hammer; an abutment therefor; a clapper and a wedge mounted between the 115 hammer and the abutment; means for actuating the hammer; and means for moving the wedge to cause it to support or release the clapper.

15. The combination of a hammer; an 120 abutment therefor; a clapper adjacent the face of the hammer but normally tending to move away from the same; a wedge between the clapper and the abutment; means for actuating the hammer; and means for 125 moving said wedge to cause it to support or release the clapper.

16. The combination in a welt beating

- machine of a hammer; an abutment therefor; a shaft; a movably mounted structure for supporting said shaft; an eccentrically placed weight on the shaft; means for driving the shaft; and means for adjustably connecting said movable structure to the hammer.
17. The combination in a welt beating device of a supporting structure; a casing mounted thereon so as to be free to vibrate; a shaft mounted in the casing; a weight eccentrically mounted on the shaft within the casing; means for driving the shaft to vibrate the casing; a hammer connected to said casing; and an abutment placed to co-operate with the hammer.
18. The combination in a welt beating device of a supporting structure; a casing mounted thereon so as to be free to vibrate; a shaft mounted in the casing; a weight eccentrically mounted on the shaft within the casing; means for driving the shaft to vibrate the casing; a hammer connected to said casing; and an abutment placed to co-operate with the hammer; with a spring placed to oppose movement of the casing.
19. The combination in a welt beating device of a structure mounted to oscillate; a shaft mounted in the structure; a weight eccentrically fixed to said shaft; means for driving the shaft; an abutment; a hammer placed to co-operate with said abutment and connected to said structure; and a work supporting saddle; with means for vibrating said saddle from said structure.
20. The combination in a welt beating machine of a work supporting structure; a hammer structurally independent of said work supporting structure; and means common to said hammer and work supporting structure for simultaneously vibrating both of said parts.
21. The combination of a band knife; a work supporting structure yieldingly mounted adjacent said knife; and means for vibrating said structure to facilitate the passage of work over the same.
22. The combination of a hammer; an abutment therefor; a band knife having its operative run adjacent the hammer; with a work supporting saddle also adjacent the knife and spaced apart from the hammer.
23. The combination of a hammer; an abutment therefor; a band knife having its operative run adjacent the hammer; with a work supporting saddle also adjacent the knife and spaced apart from the hammer; and means for vibrating said work support to facilitate the passage of work over the same.
24. The combination of a hammer; an abutment therefor; a band knife having its operative run adjacent the hammer; with a work supporting saddle also adjacent the knife and spaced apart from the hammer; and a device common to said hammer and to the work support for simultaneously vibrating said two parts.
25. The combination of a hammer having an abutment; means for actuating said hammer; a work supporting structure adjacent the hammer; and a spring for supporting said structure so as to permit it to move toward and from the hammer.
26. The combination of a hammer having an abutment; means for actuating said hammer; a work supporting structure adjacent the hammer; and a spring for supporting said structure so as to permit it to move toward and from the hammer; with means for vibrating said work supporting structure.
27. The combination of a band knife; a work support adjacent thereto; means for yieldingly supporting said structure to permit it to move substantially parallel to the operative run of said knife; and means for vibrating said work supporting structure.
28. The combination of a band knife; a work supporting saddle mounted adjacent thereto; means for supporting said saddle to permit it to move substantially parallel to the operating run of the knife; a bar movable independently of the saddle but placed to be operative thereon; and means for vibrating said bar.
29. The combination of a cutting device; a hammer mounted on one side of the plane of said device; an abutment for said hammer on the other side of said plane; a device co-operating with the abutment for supporting a welt adjacent to the hammer; and means for actuating said hammer.
30. The combination of a cutting device; a hammer mounted on one side of the plane of said device; an abutment for said hammer on the other side of said plane; a device co-operating with the abutment for supporting a welt adjacent to the hammer; and means for actuating said hammer; with a work supporting structure spaced away from said hammer.
31. The combination of a tool having a movable member; means for actuating said member consisting of a vibratory structure connected thereto; a shaft mounted in said structure; a weight eccentrically mounted on said shaft; and means for driving the shaft to turn the weight at a speed to vibrate said structure.
32. A welt beating device consisting of a hammer; an unbalanced rotary structure operatively connected to the hammer; means for actuating said rotary structure; with means for varying the weight of the structure consisting of removable screw plugs.
33. The combination with a band knife of

a hammer and an abutment therefor mounted to act on a shoe being trimmed by the knife; a vibratory structure for actuating the hammer; means normally tending to 5 force the structure toward the knife; and means for limiting the approach of said structure to the knife.

34. The combination in a band knife of a hammer placed to act on work to be 10 trimmed thereby; a supporting structure for the hammer; a vibratory structure operatively connected to the hammer; an unbalanced rotary device for vibrating the structure to actuate the hammer; and an 15 abutment mounted on the supporting structure in position to co-act with the vibratory structure to limit the approach of the hammer to the knife.

35. The combination with a band knife 20 of a work supporting structure; and means for vibrating said structure under operating conditions; the same consisting of a lever operative on the structure; a vibratory device operative on the lever; with a hammer 25 operative adjacent said work supporting structure and actuated by said vibratory device.

36. The combination in a shoe trimming machine of a band knife; a work supporting structure free to move to a limited extent in the line of said knife; a longitudinally movable member; means for rapidly reciprocating said member; and a lever for

transmitting movement from the member to the work supporting structure. 35

37. The combination with a band knife of a work supporting piece therefor; a guiding structure for said piece on which the latter is vertically movable; a lever pivoted to said structure having one arm operatively engaging said piece; an unbalanced rotary structure; means for driving the same; and a reciprocable member operatively connecting the lever and said unbalanced rotary structure for imparting a vibratory movement to the work supporting piece. 40 45

38. The combination in a device for trimming slices of a frame; a work supporting post; a band knife having a run adjacent said post; a work supporting saddle guided 50 on said post so as to be vertically movable; a spring supporting said saddle; a lever pivoted to the post and having an arm operative on the saddle; a shaft having a weight eccentrically mounted thereon; a 55 movable structure supporting said shaft and operatively connected to the lever; with means for driving the shaft.

In testimony whereof, I have signed my name to this specification, in the presence of 60 two subscribing witnesses.
